United States Patent Office

Des. 224,280

Patented July 11, 1972

224,280

SNOWMOBILE ACCESSORY CARRIER

Russell L. Price, 3275 Kenwood Ave.,
Minneapolis, Minn. 55416

Filed Sept. 30, 1970, Ser. No. 25,276

Term of patent 14 years

Int. Cl. D3—99

U.S. Cl. D87—1

FIG 1

FIG 5

FIG. 1 is a perspective view from one corner and the top of a snowmobile accessory carrier showing my new design;

FIG. 2 is a top view thereof;

FIG. 3 is a bottom view thereof;

FIG. 4 is a side view thereof; and

FIG. 5 is an end view thereof.

I claim:

The ornamental design for a snowmobile accessory carrier, as shown.
